[57] CLAIM

The ornamental design for a fully automatic systematic timekeeping clock, as shown and described.

DESCRIPTION

FIG. 1 is a top and left-front isometric view of a fully automatic systematic timekeeping clock showing our view design;

FIG. 2 is a left side elevational view thereof;

FIG. 3 is a right side elevational view thereof;

FIG. 4 is a top plan view thereof, the bottom being flat, plain, and unornamented;

FIG. 5 is a front elevational view thereof, the rear being flat, plain and unornamented.
